UNITED STATES PATENT OFFICE.

EMANUEL AUFIERO, OF BROOKLYN, NEW YORK.

TIMEPIECE.

No. 893,772.

Specification of Letters Patent.

Patented July 21, 1908.

Application filed June 6, 1907. Serial No. 377,554.

To all whom it may concern:

Be it known that I, EMANUEL AUFIERO, a citizen of the United States, residing at Brooklyn, in the county of Kings and State 5 of New York, have invented certain new and useful Improvements in Timepieces; and I do declare the following to be a full, clear, and exact description of the invention, such as will enable others skilled in the art to 10 which it appertains to make and use the same.

This invention relates to improvements in watches, clocks and the like.

The object of the invention is to provide a 15 timepiece having means for indicating the standard or local time at different longitudes.

With this object in view, the invention consists of certain novel features of construction, combination and arrangement of parts 20 as will be more particularly described and particularly pointed out in the appended claims.

In the accompanying drawings, Figure 1 is a side view of a watch constructed in accordance with the invention; Fig. 2 is a sectional view on the line 2—2 of Fig. 1; Fig. 3 is a plan view of the two stationary dials of the watch; Fig. 4 is a similar view of the revolving hour dial and Fig. 5 is a similar view 30 of the revolving minute dial.

In the embodiment of the invention I provide four concentrically arranged dials, two of which are stationary, and two revolving. On one of the stationary dials is indicated by 35 numerals of reference how many minutes a certain city is east or west of a given standard hour meridian. On the other stationary dial is indicated the names of the principal cities of the world. On one of the revolving 40 dials is indicated an hour scale, and on the other revolving dial is indicated a minute scale.

The central stationary dial *i* is divided into equal parts by twelve radii, and the dotted circle *p* divides each radial line into two parts. The parts of the radial lines within the circle *p* represent the twelve standard meridians of west longitude, and the parts of the radial lines on the outside of said circle 50 represent the twelve standard meridians of east longitude. As shown in Fig. 3 of the drawings, each of the radial lines is provided with a numeral which indicates the counting value of said line. The international meridian of Greenwich may be represented by the radial line on which London is written. The

radial line numbered 1 next to the left of the London line indicates one hour east of Greenwich; the radial line numbered two indicates two hours east of Greenwich, and so on. As 60 illustrative of this, Rome which is one hour, standard time, east of Greenwich is written on the line 1.

The radial line numbered 1 on the right of the London meridian indicates one hour west 65 of Greenwich; the line numbered two reads 2 hours west of Greenwich, and so on. As an illustration of this, Washington, which is five hours west of Greenwich is indicated on the line 5 within the circle *p*.

The names of the cities are written on that hour line, the longitude and time of which is nearest to or exactly the longitude and time of the said city. To each of the cities of which the time is not exactly represented by 75 the hour line, is annexed a reference numeral which is reproduced on the stationary dial, *j*, as shown. This reference numeral indicates the number of minutes the said city is east or west of the hour meridian. The names of the 80 cities on the inner stationary dial are written across the hour lines which pass through or between the central letters of the city, so that one-half of the letters of the city are on one side of the line, and the other half on the 85 opposite side.

The annular stationary dial *j* is divided into sixty equal parts or minutes, of which thirty are on a white background, and thirty on a light blue background, the latter being 90 indicated in the drawings by diagonal shade lines. The arrow head, *n*, which separates the white half from the blue half of the dial, is arranged in line with the London or Greenwich meridian line of the inner stationary 95 dial. One minute east of any standard meridian indicated on the dial *i* is represented by the division mark or next on the left of the arrow head, *n*. The second division indicates two minutes east and so on until the 100 thirtieth division on the white half of the dial is reached. In the same manner the divisions or minutes are counted on the shaded or blue side on the right of the arrowhead, *n*, the division mark annexed on the right of 105 said arrow head indicating one minute west, and the second mark two minutes west and so on.

As hereinbefore described, the number of references annexed to a city is reproduced on 110 the dial *j*, and its position thereon indicates the number of minutes the said city is east

or west of the hour meridian on which the city is written. As an illustration, the number 8, which is annexed to Buenos Ayres is reproduced on the seventeenth division of the 5 dial *j* to the left of the arrow head *n*, and is read seventeen minutes east or ahead of the hour meridian on which said city is placed. The number 6, which is annexed to Singapore, is reproduced on the fifth division on the 10 shaded or blue half of the dial, and is read five minutes west or past the hour. The outer stationary dial *j* has arranged thereon, adjacent to its outer edge, a series of arrow heads, which indicate continuations of the 15 meridian lines on the dial *i*. The inner dial *i* and the outer concentrically arranged annular dial *j* are spaced apart and connected together by radially projecting bars, *k*², as shown in Fig. 3 thus providing between said 20 dial an annular space, *k*³, in which the inner revolving dial is adapted to rotate. Formed on the outer edge of the outer annular dial *j* are radially projecting bars, *k* by means of which said stationary dials are firmly secured 25 to the casing of the watch. The outer revolving dial *d* incloses the stationary dial *j* and revolves around the same. On the dial *d* is arranged Roman numerals from one to twelve, said numerals being disposed 30 reversely to the position in which they are usually placed on the face of an ordinary clock or watch. Any suitable form of time piece movement may be arranged in the casing of the watch to operate the movable dials there- 35 in. The dial *d* is mounted on the hour sleeve *c* of the movement, which is indicated by the reference letter M in Fig. 2. The dial *d* is adapted to turn from left to right with the sleeve *c* of the movement. The revolving 40 minute dial *b* is fixed to the minute shaft of the movement and turns therewith so as to make one complete revolution for each hour that the dial *d* moves. The dial *d* is arranged and turns in the space *k*³ between the inner 45 and outer stationary dials, and is divided into sixty equal parts or minutes, of which thirty are designated by black marks, or lines, opposite every five of which is placed a black indicating numeral. The other thirty di- 50 visional lines of the dial are designated by lines or marks upon a blue background, which is indicated in the drawings by diagonal shading. Opposite every five of these divisional marks is placed a numeral. The 55 numeral sixty is placed on the division line separating the white half of the dial from the shaded half. The numerals of each side of the number sixty begin with five and increase up to thirty, which numeral is arranged dia- 60 metrically opposite to the numeral sixty, as shown. At the beginning of each hour, the numeral sixty on the dial *b* is coincident with the arrow head *n* of the outer stationary dial *j*. 65 The dials employed in connection with my

invention may be constructed of celluloid, smelted copper, or any other suitable material, and as hereinbefore described, may be connected with and operated by any suitable time piece movement. In order to cause the 70 greatest contrast between the different cities on the various meridians, I prefer to print such cities in different colors, as red, green, blue, yellow, etc., using the same color for all cities belonging on the same meridian. The 75 arrow heads on the dial *j* are also printed in the same color as the meridian to which they correspond.

In reading the device to ascertain the time of such cities which have no annexed reference numeral, the minute sign on the dial *b* nearest to the arrow head *n* is read; if said minute sign is on a white ground, read the hour on the dial *d*, which has just crossed or passed the hour mark or arrow head of the 85 city, the time of which it is desired to find. If the minute sign nearest to the arrow head *n* is on a blue ground, read the hour on the opposite side of the arrow head *n* or about to cross the same. When it is desired to find 90 the time of the cities to which reference numerals are annexed, read on the minute dial *b* the minute sign nearest to the division on the dial *j* having reproduced thereon the numeral which is annexed to said city, this 95 division being for the sake of reference called the "minute point" of the city, the minute point of a city having no reference numeral added is the arrow marked "London."

In all cases when the minute sign on the 100 dial *j* opposite the minute point of a city is on a white ground, read the time of that city as so many minutes past, or after the hour. If a minute sign is on the blue ground, read the time as so many minutes to or before the 105 hour. The hour is found as follows: First. When the minute point of the city is on a white ground, if the minute signs opposite the minute point and opposite the arrow marked "London" are both on a white 110 ground, the hour which has just crossed the hour meridian of said city is read; if not, the hour which is about to cross is read. Second. When the minute point is on a blue ground, if the minute signs opposite the minute point and opposite the arrow marked "London" are both on a blue ground, the hour about to cross the hour meridian of the 115 city is read; if not, the hour which has just crossed is read.

The ante meridiem or post meridiem time is determined by the meridian, the time of which is known, and the rule to be followed is to count from the meridian nearest to the hour 1 to the meridian nearest to the hour 12, the longitude being changed by crossing the meridian of Greenwich, except when the hour twelve is precisely on this meridian. For instance, at Washington it is six o'clock, post meridiem. The longitude 130

- of Washington is west, therefore, the western meridians from the meridian nearest to the hour on the dial *d* to the meridian of Greenwich read post meridiem time. Changing 5 longitude, the eastern meridians from the meridian of Greenwich to the meridian nearest to the hour twelve read post meridiem time. The other twelve meridians read ante meridiem time.
- 10 From the foregoing description, taken in connection with the accompanying drawings, the construction and operation of the invention may be readily understood without requiring a more extended explanation.
- 15 Various changes in the form, proportion and the minor details of construction may be resorted to without departing from the principle or sacrificing any of the advantages of this invention as defined in the appended 20 claims.

Having fully described my invention, what I claim as new and desire to secure by Letters-Patent, is:

1. A time piece of the character described, 25 provided with a centrally disposed stationary dial having arranged thereon radially disposed lines representing the meridians of longitudes, which are divided midway between their ends to indicate east and west 30 longitude, an outer annular stationary dial arranged concentrically to said inner dial and spaced therefrom, said outer dial having arranged thereon divisions indicating minutes of longitude, an annular revolvably mounted 35 minute dial arranged between said inner and outer stationary dials, and having indicated thereon radial divisions representing minutes of time, and an outer revolvably mounted dial arranged around said outer stationary dial, 40 said outer movable dial having indicated thereon radial division lines representing hours of time, substantially as described.

2. A time piece of the character described, 45 comprising a casing, an inner circular centrally disposed stationary dial having arranged thereon meridian lines of longitude, an outer annular stationary minute dial arranged concentrically to and spaced from said inner stationary dial, an inner revolvably 50 mounted annular dial arranged in the space between said stationary dials and adapted to be operatively mounted on the minute pin of the time piece movement, said dial having arranged thereon divisional marks indicating 55 minutes of time, and an outer revolvably mounted dial adapted to be operatively connected to the hour sleeve of the time piece

movement, said outer dial having arranged thereon divisional marks indicating hours of time, substantially as described. 60

3. A time device provided with a central stationary circular dial having meridial lines and divided into central and outer parts on which the location of certain places is indicated, a stationary annular minute dial, an 65 annular movable minute dial connected with the minute shaft of the time mechanism, and an annular hour dial connected with the hour sleeves of the time mechanism, all of said dials being concentrically arranged. 70

4. A time device provided with a central stationary circular dial having meridial lines and divided into central and outer parts on which the location of certain places is indicated, a stationary annular minute dial, an 75 annular movable minute dial connected with the minute shaft of the time mechanism, and an annular hour dial connected with the hour sleeve of the time mechanism, all of said dials being concentrically arranged, the movable 80 minute dial being divided into two parts containing sixty minutes divided into two series of thirty minutes each, the stationary minute dial being divided into sixty minutes and the hour dial being divided into twelve hours 85 reading from right to left.

5. A time device provided with a central stationary circular dial having meridial lines and divided into central and outer parts on which the location of certain places is indicated, a stationary annular minute dial, an 90 annular movable minute dial connected with the minute shaft of the time mechanism, and an annular hour dial connected with the hour sleeve of the time mechanism, all of said dials 95 being concentrically arranged, the movable minute dial being divided into two parts containing sixty minutes divided into two series of thirty minutes each, the stationary minute dial being divided into sixty minutes and the 100 hour dial being divided into twelve hours reading from right to left, certain places on the central dial being provided with numbers and the stationary minute dial being provided at certain points with corresponding numbers. 105

In testimony whereof I have hereunto set my hand in presence of two subscribing witnesses.

EMANUEL AUFIERO.
